DOOR OPENING AND DOOR CHECKING DEVICE

Rudolph I. Schonitzer, Shaker Heights, Ohio

Application February 5, 1940, Serial No. 317,300

9 Claims. (Cl. 16—85)

This invention relates to door opening devices and to combined door opening and door checking devices, said devices preferably being of such character that they yieldingly resist (but only to a desirable degree) the closing of the doors with which they are used from the open positions to which said doors are automatically movable by said devices. As will hereinafter appear, devices embodying the present invention are particularly adapted for use with doors which are so hinged on their supporting structures that the hinge edge walls of said doors and the hinge edge walls of said supporting structures are in oppositely positioned or generally abutting relationship when said doors are in their closed positions, such as the doors of automobiles or the like, for example.

One of the objects of the present invention is the provision of a device which comprises expandable means for association with, and which is effective at all times on, a hinged door and the supporting structure therefor, said expandable means being put in the desired loaded condition during the closing of the door and being capable, by its expansion, of automatically effecting, upon the unlatching of said door, the movement of said door to any desired open position, either a partially open position or the fully open position of said door. Preferably, said expandable means is of such character and of such compact form that it may be associated with (such as by being pivotally connected to) said door and its supporting structure between the general planes of the inner and outer side walls thereof, all as will herein-after more fully appear.

Another object of the present invention is the provision of a device which comprises a pair of relatively movable elements inlapping relationship and by one or both of which is carried a compression spring or the like, one of said elements, in the use of said device, having pivotal connection to, or other suitable association with, the door to be automatically opened, and the other of said elements having pivotal connection to, or other suitable association with, the supporting structure for said door.

Another object of the present invention is the provision of a combined door opening and door checking device which is effective, upon the unlatching of the door with which it is used, to automatically open said door to any desired extent, and to check or arrest the opening movement of said door when it reaches its fully open position, thereby making wholly unnecessary the use of separate means for such door checking purpose.

Another object of the present invention is the provision of a device which is effective, upon the unlatching of the door with which it is used, to automatically open said door to any desired extent, to check the opening movement of said door when it reaches its fully open position, and to yieldingly resist (but only to a desirable degree) the closing of said door from the open position to which it is automatically movable.

Other features of devices embodying the present invention are their structural simplicity, which enables them to be made and sold at low cost; their strong and rugged character, which enables them to have an exceedingly long life in service without requiring attention from time to time; and the efficiency with which they perform their intended functions, namely, the function of automatically opening to any desired extent the doors with which such devices are used and the function of yieldingly resisting (but only to a desirable degree) the closing of said doors from the positions to which they are automatically opened; or those two functions with the additional function of checking or arresting the opening movement of said doors when they have reached their fully open positions.

Further features of devices embodying the present invention are in part obvious and in part will appear from the following description of three of such devices, reference being had to the accompanying drawings, in which

Fig. 1 is an outside elevation of a portion of a left front automobile door and that portion of the automobile body on which said door is hinged, parts of the outer side walls of said door and body portions being broken away to show the combined door opening and door checking device associated therewith, the door being in its closed position; Fig. 2 is a horizontal sectional view, on an enlarged scale, through said door and body portions, the view being on the line 2—2, Figs. 1 and 3; Fig. 3 is a vertical sectional view through said door and body portions, on the line 3—3, Fig. 2; Fig. 4 is a vertical sectional view through said body portion, on the line 4—4, Fig. 2; Fig. 5 is a view corresponding to Fig. 2 but showing the door in its fully open position; Fig. 6 is a perspective view of one of the end members of such door opening and door checking device, said end members being the parts which are pivotally connected to said door and body portions; Fig. 7 is a perspective view of the other end member of such device; Fig. 8 is a view corresponding to Fig. 2 but showing the door opening and door checking device of Figs. 1 to 7 in-

- clusive reversely connected to a left front automobile door and its supporting body portion; Fig. 9 is a view corresponding to Fig. 5 but showing said door opening and door checking device 5 as secured in Fig. 8; Fig. 10 is an axial section of a modified form of a door opening and door checking device embodying the present invention; and Fig. 11 is an axial section of still another form of a door opening and door checking device 10 embodying the present invention.

Before the present invention is described in detail, it is to be understood that such invention is not limited to the details of construction or the specific arrangement of parts herein illustrated 15 or described, as the invention obviously may take other forms. It also is to be understood that the phraseology or terminology herein employed is for the purpose of description and not of limitation.

- 20 Although devices embodying the present invention are applicable for use with any hinged door having its hinge edge wall oppositely positioned or in generally abutting relationship with respect to the hinge edge wall of its supporting structure 25 (the structure on which said door is hinged), the devices here involved are particularly useful, as heretofore pointed out, with the doors of automobiles or the like, and for purposes of illustration and not of limitation, the use of one of such 30 devices with present-day automobile doors is here shown and described.

Referring first to Figs. 1 to 7 inclusive, the reference numeral 1 designates a portion of a left front automobile door, said door having its transverse front edge wall 2 suitably hinged, as is usual, on the transverse rear edge wall 3 of that portion of the automobile body shown in Figs. 1 to 5 inclusive and designated generally by the reference numeral 4, a pair of exposed hinges 5 being used for that purpose, and the door hinge axis being indicated by the reference numeral 6. As best shown in Fig. 2, when the door 1 is in its closed position, the door and body edge walls 2 and 3 (which edge walls are hereinafter termed 45 "hinge edge walls") are in oppositely positioned or generally abutting relationship, by which is meant that such hinge edge walls are oppositely positioned or disposed and either in actual contact, or, as here shown, relatively close to each 50 other.

Although any suitable means may be utilized 55 for releasably retaining the door 1 in its closed position and for actuating said retaining means to release said door for opening movement, (said retaining means being hereinafter referred to broadly as "latch means") devices embodying the present invention are particularly useful in conjunction with doors whose latch means have push-buttons or the like for effecting release actuation of said latch means, as opening movement of said doors, to any desired extent, is automatically effected by the invention here involved. Projecting handles by the use of which present-day automobile doors are unlatched and manually 60 opened, not only are dangerous (in that many severe injuries have been caused by them) but also, said projecting handles seriously interfere with the streamlining effects now desired for automobile bodies. Inasmuch as a device embodying the present invention automatically effects, upon the unlatching of the door with which it is used, the opening of said door to its fully 65 open position, the use with such a door of the present-day handles for door opening purposes 70 is wholly unnecessary. As a result, simple push-

buttons or the like, desirable from many standpoints, may be used with the latch means of a door with which is used an automatic opening device of the character here involved.

The latch means, therefore, of the automobile door 1 of Figs. 1 to 5 inclusive may be, and preferably is, of the type in which push-buttons or the like are utilized for effecting release actuation thereof. For example, said latch means may be of the form disclosed in my copending application for Door opening devices, filed August 21, 1939, Serial No. 291,240, or in other words, latch means embodying the invention of my prior Patent No. 2,094,413 for Door control mechanism, to which patent reference may be had, if desired. However, inasmuch as the latch means of the door 1 forms no part of the present invention, no latch means for such door is here shown or described.

As will hereinafter more fully appear, each of the devices here illustrated (devices which are capable of automatically swinging relatively heavy doors, such as present-day automobile doors, to partially open positions thereof or to their fully open positions) is of simple and inexpensive character and of such compact form that it may be easily and conveniently mounted between the general planes of the side walls of an automobile door and the general planes of the side walls of that portion of the automobile body on which said door is hinged, there being (see Figs. 2 and 8) more or less alignment of the outer side walls of such door and such a body portion and more or less alignment of the inner side walls of such door and such a body portion, when said door is in its closed position. As a result, the devices here involved not only are eminently satisfactory from structural and functional standpoints but also, are commercially practical for present-day automobile doors, as such devices are concealed from view when the doors with which they are used are in their closed positions, and the extent of their exposure, even when such doors are in their fully open positions, is such that said devices are entirely unobjectionable.

Although devices embodying the present invention may take various forms, as will be readily understood and as will hereinafter more fully appear, each of said devices, in its broader aspects, comprises expandible means for association with, and which is effective at all times on, the door to be automatically opened and the supporting structure therefor.

Three specific forms which devices embodying the present invention may take are here illustrated, and each of those devices includes an expandible part, in the form of a coiled compression spring, and a pair of relatively movable, elongated elements by one or both of which said compression spring is carried and guided during expansion and contraction thereof. Preferably, said elements are in lapping relationship (telescopic relationship, as here shown), and in the here disclosed use of the device of which they are parts, the front end portion of one of said elements and the rear end portion of the other are pivotally secured by means of brackets or otherwise to the door to be automatically opened and to the supporting structure therefor. During the closing of the door with which such device is used, the coiled compression spring of such device is compressed and thereby put in the desired "loaded" condition, and upon the unlatching of said closed door, said spring expands and thereby automatically effects the movement of said door to

any desired open position, as will more fully appear.

In addition to automatically opening to the extent desired the doors with which the present devices are used, said devices yieldingly resist, to any desired degree, the closing of said doors from the open positions to which they are automatically movable, the degree of such door closing resistance being dependent, of course, upon the compression resistance of the springs of such devices when said doors are in such open positions. Therefore, by the selection of a spring having the proper compression resistance when the door with which it is used is in the open position to which it is automatically movable, any desired resistance to door closing movement can be obtained, as will be readily understood.

Furthermore, devices embodying the present invention, (such as the device illustrated in Figs. 1 to 9 inclusive, for example) may, if desired, determine the fully open positions of the doors with which such devices are used, or in other words, determine the extent to which such doors can be opened, thereby making wholly unnecessary the use with said doors of separate checking means such as are now used with automobile doors for yieldingly or otherwise checking or arresting the movement of said doors when they have been manually swung to their fully open positions.

Referring now to the device illustrated in Figs. 1 to 9 inclusive, it will be noted that such device comprises a pair of telescopically related members, one of said members being in the form of a tube 8 and the other being in the form of a bolt 9, the head 10 of said bolt being disposed within said tube at all times. Surrounding said tube and said bolt is a coiled compression spring 12, the ends of which bear against suitable abutments with which said tube and said bolt are provided. As here shown, the front end of said tube and the rear end of said bolt are provided with simple and inexpensive sheet metal end pieces, which not only constitute the abutments for the ends of the compression spring 12 but also, constitute the means by which said tube and said bolt are pivotally secured to the automobile door 1 and the automobile body portion 4 on which said door is hinged.

The sheet metal end piece 14 here shown (see Fig. 7) for the tube 8 comprises a substantially flat abutment portion 15 having a centrally disposed aperture to enable it to be mounted on the front end portion of said tube, and a pair of generally parallel perforated ears 16 which project, when said end piece is mounted upon the front end of said tube, forwardly beyond said tube and thereby provide a means for enabling said tube to be pivotally secured either to the automobile door 1 or to the automobile body portion 4. To retain said end piece on the front end of said tube, said tube is provided at its front end with an annular flange 17, which may be economically formed as an integral part of said tube by a swaging operation or the like. As shown, said tube flange 17 extends radially outward and provides a rigid backing for the abutment portion 15 of the tube end piece, and as said abutment portion is firmly held against said tube flange by the compression spring 12, the assembly with said tube of its end piece is securely maintained.

The end piece 19 here shown (see Fig. 6) for the bolt 9 comprises a substantially flat abutment portion 20 having a centrally disposed aperture

to enable it to be mounted on the threaded rear end of said bolt, and a pair of converging perforated ears 21 which project, when said end piece is mounted upon the outer end of said bolt, rearwardly beyond said bolt and thereby provide a means for enabling said bolt to be pivotally secured to either the door 1 or the automobile body portion 4. To retain said end piece on the rear end of said bolt, said bolt has threaded on its rear end a nut 22, rotation of which nut relative to said end piece is prevented by the ears 21 of said end piece. As will be readily understood, said nut provides a rigid backing for the abutment portion 20 of the bolt end piece, and as such abutment portion is firmly held against said nut by the compression spring 12, the assembly with said bolt of its end piece is securely maintained.

As here shown, the relative diameters of the tube 8 and the compression spring 12 are such that said spring more or less snugly surrounds said tube, and as a result, there is no liability of lateral displacement of that end of the spring which engages the abutment portion 15 of the tube end piece 14. In order to prevent, however, any lateral displacement of that end of the compression spring which engages the abutment portion 20 of the bolt end piece 19, said abutment portion is here provided, at its periphery, with laterally bent flanges 23, the effect of which is to provide for this end of the compression spring 30 a socket or the like which effectively prevents lateral displacement thereof. If desired, and as here shown, the socket forming flanges 23 of the end piece 19 may be integral parts of the metal of which such end piece is formed, the formation 35 of such end piece being effected by simple shearing and stamping operations.

As heretofore pointed out, either of the two telescopically related members of the device of Figs. 1 to 9 inclusive may be pivotally secured to the automobile door 1. That is to say, the tube 8 may be pivotally secured to the door 1 and the bolt 9 pivotally secured to the automobile body portion 4, or the bolt 9 may be pivotally secured to such door and the tube 8 pivotally secured to such body portion. In either case, the tube and the bolt are pivotally secured to said door and said body portion between the general planes of their inner and outer side walls, the general plane of any such side wall, as that term is here used, being the plane which not only includes such side wall but which extends therebeyond.

In Figs. 1 to 5 inclusive of the accompanying drawings, the bolt 9 is pivotally secured to the automobile door 1, between the general planes of its inner and outer side walls 24 and 25, and the tube 8 is pivotally secured to the automobile body portion 4, between the general planes of its inner and outer side walls 26 and 27. As there shown, the perforated ears 21 of the bolt end piece 19 are pivotally secured, by the use of a rivet 28 or the like, to a bracket with which said door is suitably provided, such as to a bracket 29 secured to the hinge edge wall 2 of said door; and the perforated ears 16 of the tube end piece 14 are pivotally secured, by the use of a rivet 30 or the like, to bracket means with which said body portion is suitably provided, such as to the brackets 31 secured to the inner side wall 26 of said body portion some distance forwardly of its hinge edge wall 3. Such a mounting requires, of course, the provision of a suitable opening, such as the transverse slot 33 here shown, in said hinge edge wall for the extension therethrough of the bolt 9 and the compression spring 12 dur-

ing opening and closing movements of the door 1, and if the automobile body portion 4 is provided with a reinforcement pillar, such as the one here shown, it is also necessary to provide a suitable opening, such as the transverse slot 35 here shown, in the transverse wall 34 of said pillar. Although the slots 33 and 35 must be in alignment, they need not be, and here are not, co-extensive in length (see Fig. 4).

10 For the accomplishment of its door checking function, the device of Figs. 1 to 5 inclusive is provided with means for limiting the movement of its bolt 9 with respect to its tube 8 during opening movement of the door with which such device is used, and inasmuch as said bolt is connected to and moves with said door, the arresting of bolt movement in a door opening direction also arrests, as will be readily understood, corresponding movement of said door.

15 As here shown, the device of Figs. 1 to 5 inclusive has the rear end of its tube 8 turned radially inward to provide an annular abutment flange 37, the location of said flange, with respect to the head 10 of the bolt 9, being such that said flange is engaged by said bolt head—or by a resilient cushioning member associated therewith, such as the rubber disc 38 here shown—when the door with which such device is used has reached its fully open position. As a result, the movement of the bolt 9 in a door opening direction, and the corresponding movement of the door to which said bolt is pivotally connected, are limited or arrested, as desired, and it is therefore wholly unnecessary to provide for said door a 20 separate checking means for the purpose of checking or arresting its opening movement when said door has reached its fully open position.

Instead of having such door opening device extend into the automobile body portion, as in Figs. 1 to 5 inclusive, said device may extend into the automobile door, and such a reverse mounting is illustrated in Figs. 8 and 9. As there shown, the tube 8 is located within the left front automobile door 1a, the end piece 14 of such tube being pivotally connected to a bracket 31a suitably secured to the inner side wall 24a of said door some distance rearwardly of its hinge edge wall 2a; and the end piece 19 of the bolt 9 is 25 pivotally connected to a bracket 29a suitably secured to the hinge edge wall 3a of the automobile body portion 4a. With such a mounting, it is, of course, merely necessary to provide a suitable opening, such as the transverse slot 33a 30 here shown, in the hinge edge wall 2a of the door 1a, for the extension therethrough of the bolt 9 and the compression spring 12, during opening and closing movements of said door, all as will be readily understood.

35 60 With either mounting, the compression spring 12, during the manual movement to closed position of the door with which it is used, will be compressed (as in Figs. 1 to 3 inclusive and Fig. 8) and thereby put in desired "loaded" condition, and upon the unlatching of said door, said spring will automatically effect, by the force of its expansion, the movement of said door to either a partially open position, or as here shown, to its fully open position, the position of the door 1 in Fig. 5 and the position of the door 1a in Fig. 9. If it is desired that either the door 1 or the door 1a be automatically movable to a partially open position only (and manually movable to its fully open position), it is merely 40 necessary to have weaker or shorter, or both,

the coiled compression spring of the device which is used with said door, or in other words, to have said spring of such character that it is incapable of automatically moving said door beyond the desired partially open position, all as will be readily understood.

45 As heretofore pointed out, devices embodying the present invention not only automatically effect, upon the unlatching of the doors with which they are used, the opening of said doors to the extent desired but also, yieldingly resist the closing of said doors from the positions to which they are automatically opened. Moreover, devices embodying the present invention also may effect, if desired, the checking or arresting of the opening movement of the doors with which such devices are used when said doors reach their fully open positions, as will be readily understood from the foregoing description of the device of Figs. 1 to 9 inclusive. Inasmuch as 50 the compression spring 12 of the device of Figs. 1 to 9 inclusive is effective to fully open the door 1 or the door 1a, closing movement of either door from its fully open position is yieldingly resisted, and as a result, said door is releasably held or 55 retained in its fully open position whenever it is moved thereto. With the device of Figs. 1 to 9 inclusive, therefore, no separate holding means is necessary for releasably retaining the door with which said device is used in its fully open 60 position. If, on the other hand, the door 1 or the door 1a is automatically movable by the device of Figs. 1 to 9 inclusive to a partially open position only, and if the releasable retention of said door in its fully open position is desired, 65 the use of separate holding means for said door is necessary for that purpose, although the closing of said door from said partially open position would be yieldingly resisted, of course, by said device. Therefore, if said door had a normal tendency to close, like most present-day 70 automobile doors, it remains in the partially open position to which it is automatically movable, unless it were manually closed or manually moved to a further open position, all as will be readily understood.

75 In Figs. 10 and 11, two modified forms of devices embodying the present invention are illustrated, devices which include, in addition to coiled compression springs, telescopically related members of tubular form. In the device of Fig. 10, there is an outer tube 8a and an inner tube 8b, and said telescopically related tubes are surrounded by a coiled compression spring 12a. The ends of said spring abut or engage, as here shown, suitable end pieces 14a with which the outer ends of said tubes are provided, said end pieces, if desired and as here shown, being identical with the sheet metal end piece 14 heretofore described and being maintained in assembly with the tubes 8a and 8b in the same manner in which the end piece 14 is maintained in assembly with the tube 8 of the device of Figs. 1 to 9 inclusive. For the pivotal connection of the device of Fig. 10 to a door structure and its supporting structure, such as to an automobile door and that portion of the automobile body on which said door is hinged, suitable brackets, such as the simple sheet metal brackets 40 shown in Fig. 10, may be utilized, all as will be readily understood.

80 In the device of Fig. 11, a coiled compression spring 12b is arranged within the telescopically related inner and outer tubes 41 and 42. Extending transversely through the rear end portion of the inner tube 41 and the front end por-

tion of the outer tube 42 are rivets 43 or the like by which said tubes are pivotally connected to attaching brackets 40a, and although said rivets may serve, if desired, as the abutments for the ends of the compression spring 12b, the ends of said spring here engage sheet metal abutment members 45 of generally cup-shape, the cylindrical side walls of said abutment members being suitably slotted to enable them to be mounted, 10 by endwise movement thereof, upon said rivets, all as will be readily understood.

Inasmuch as the devices of Figs. 10 and 11 are adapted to be pivotally secured to a door structure and its supporting structure, such as 15 to an automobile door and that portion of the automobile body upon which said door is hinged, in substantially the same manner as the device of Figs. 1 to 9, and inasmuch as the devices of Figs. 10 and 11 operate in substantially the same 20 manner as the device of Figs. 1 to 9 to automatically open to the desired extent the doors with which they are used and to yieldingly resist the closing of said doors from the open positions to which said doors are automatically movable, no 25 further reference to the devices of Figs. 10 and 11 is believed to be necessary. It should be pointed out, however, that neither the device of Fig. 10 nor the device of Fig. 11 is shown as provided 30 with means for limiting the opening movement of the door with which it is used. However, either of those devices can be made to accomplish that result by providing its telescopically related members with means for limiting their extension or elongation, as in the device of Figs. 1 to 9 inclusive and as will be readily understood.

Further features and advantages of the present invention will be readily apparent to those skilled in the art to which it relates.

What I claim is:

40 1. A device for automatically swinging to an open position a closed but unlatched door structure so hinged on a supporting structure that the hinge edge walls of said structures are in oppositely positioned relationship when the door 45 structure is closed, said device comprising a pair of lappingly related elements, one pivotally secured to each of said structures between the general planes of its two side walls, and expansible means cooperable with said elements, said expansible means being put in the desired loaded condition during the closing of the door structure and being effective when so loaded to automatically swing said closed door structure, if unlatched, to an open position.

55 2. A device for automatically swinging to an open position a closed but unlatched door structure so hinged on a supporting structure that the hinge edge walls of said structures are in oppositely positioned relationship when the door 60 structure is closed, said device comprising a pair of elements, one pivotally secured to each of said structures between the general planes of its two side walls, expansible means carried by said elements, said expansible means being put in the desired loaded condition during the closing of the door structure and being effective when so loaded to automatically swing said closed door structure, if unlatched, to an open position, and 65 means associated with at least one of said elements for limiting the automatic opening movement of said door structure.

3. A device for automatically swinging to an open position a closed but unlatched door structure so hinged on a supporting structure that the 70 hinge edge walls of said structures are in oppo-

sitely positioned relationship when the door structure is closed, said device comprising elongated expansible means having one of its end portions pivotally secured to the hinge edge wall of one of said structures and having its other end portion located within and pivotally secured to the other of said structures between the general planes of its two side walls, said expansible means being put in the desired loaded condition during the closing of the door structure and being effective when so loaded to automatically swing said closed door structure, if unlatched, to an open position. 5

4. A device for automatically swinging to an open position a closed but unlatched door structure so hinged on a supporting structure that the hinge edge walls of said structures are in oppositely positioned relationship when the door structure is closed, said device comprising elongated expansible means pivotally associated with each of said structures between the general planes of its two side walls, said expansible means being put in the desired loaded condition during the closing of the door structure and being effective when so loaded to automatically swing said closed door structure, if unlatched, to an open position. 15

5. A device for automatically swinging to an open position, a closed but unlatched door structure so hinged on a supporting structure that the hinge edge walls of said structures are in oppositely positioned relationship when the door structure is closed, said device comprising a pair of elements, one pivotally secured to each of said structures between the general planes of its two side walls, and expansible means carried by said elements, said expansible means being put in the desired loaded condition during the closing of the door structure and being effective when so loaded to automatically swing said closed door 20 structure, if unlatched, to an open position. 30

6. A device for automatically swinging to an open position a closed but unlatched door structure so hinged on a supporting structure that the hinge edge walls of said structures are in oppositely positioned relationship when the door structure is closed, said device comprising a pair of elements, one pivotally secured to each of said structures between the general planes of its two side walls, expansible means carried by said elements, said expansible means being put in the desired loaded condition during the closing of the door structure and being effective when so loaded to automatically swing said closed door 40 structure, if unlatched, to an open position. 45

50 7. A device for automatically swinging to an open position a closed but unlatched door structure so hinged on a supporting structure that the hinge edge walls of such structures are in oppositely positioned relationship when the door structure is closed, said device comprising a pair of elements, one pivotally secured to each of said structures between the general planes of its two side walls, expansible means guided by said elements and confined between two abutments, one 55 associated with each of said structures, the confinement of said expansible means between said abutments during the closing of the door structure effecting the loading of said expansible 60

65 70 75 structure.

- means and said expansible means when so loaded being effective to automatically swing said closed door structure, if unlatched, to an open position, and opposing abutments carried by said 5 elements for limiting by their engagement with each other the extent to which said door structure can be opened.
8. A device for automatically swinging to an open position a closed but unlatched door structure so hinged on a supporting structure that the hinge edge walls of such structures are in oppositely positioned relationship when the door structure is closed, said device comprising a pair 10 of elements, one pivotally secured to each of said structures between the general planes of its two side walls, expansible means, abutments carried by said elements and between which said expansible means is confined, the confinement of said expansible means between said abutments during 15 the closing of the door structure effecting the loading of said expansible means and said expansible means when so loaded being effective to automatically swing said closed door structure, if unlatched, to an open position, and other abut- 20

ments carried by said elements for limiting by their engagement with each other the extent to which said door structure can be opened.

9. A device for automatically swinging to an open position a closed but unlatched door structure so hinged on a supporting structure that the hinge edge walls of such structures are in oppositely positioned relationship when the door structure is closed, said device comprising a pair 5 of elongated elements, one pivotally secured to 10 each of said structures between the general planes of its two side walls, expansible means surrounding said elements, said expansible means being put in the desired loaded condition during the closing of the door structure and being effective 15 when so loaded to automatically swing said closed door structure, if unlatched, to an open position, one of said elements being of tubular form for the telescopic reception of the other and said elements having opposing abutments for limiting 20 by their engagement with each other the extent to which said door structure can be opened.

RUDOLPH I. SCHONITZER.
